UNITED STATES PATENT OFFICE

ALONZO R. KEELER, OF ALTONA, ILLINOIS

CORN-SNAPPING ROLLS AND THE LIKE

Application filed March 5, 1928. Serial No. 259,229.

This invention has to do with an improved form and construction of corn snapping rolls and the like. That is to say it has to do with improvements in the rolls which serve 5 to remove the ears of corn from the stalks. These rolls are incorporated into machines whose function is to gather the ears from the stalks; but inasmuch as the snapping rolls herein illustrated and described may 10 be used in connection with various forms of corn gathering machine I do not herein illustrate the details of construction nor the assembly features of such machine.

One of the objects of the invention is to 15 provide an improved construction of snapping rolls such that the corn stalks will readily and regularly enter between said rolls as the corn gathering machine advances through the field, so that the corn stalks 20 will be almost unfailingly subjected to the action of the rolls. In this connection it is a further object to provide a construction 25 of rolls such that when the corn stalks have been delivered between them actions of the rolls will surely and certainly remove the ears from the stalk and substantially without damage to the kernels and without shell- 30 ing.

Another feature of the invention relates 35 to the provision of a built up construction of rolls of a type such that the same can be easily manufactured according to standard and well accepted manufacturing methods and processes.

Other objects and uses of the invention 40 will appear from a detailed description of the same which consists in the features of construction and combinations of parts hereinafter described and claimed.

In the drawing:

Figure 1 shows a face view of a pair of companion rolls embodying the features of the present invention, the end portions of one roll being shown in section so as to better 45 illustrate the interior construction and the method of mounting on the shaft;

Fig. 2 shows a cross section on the line 2—2 of Fig. 1 looking in the direction of the arrows but on enlarged scale; and

Fig. 3 shows a cross section on the line

3—3 of Fig. 1 looking in the direction of the arrows but on enlarged scale.

The two rolls of the pair are designated by the numerals 5 and 6. They are of the same construction with the exception of the 55 fact that the end ribs of the two rolls spiral in opposite directions.

Each roll includes a substantially cylindrical body section 7 the rear end portion of which is substantially straight and of larger 60 size than the front portion 8 which is of somewhat smaller size and tapered towards its front end as clearly shown in Fig. 1. Both portions of each roll are substantially circular at different sections but the rear portion 65 is ribbed as will be presently explained.

There is a slight shoulder 9 at the point of joinder of the cylindrical and tapered portions of each roll, and this shoulder is preferably relatively shallow as for example ap- 70 proximately $\frac{1}{8}$ of an inch.

The total length of the roll proper is conveniently made approximately 45 inches of which the front tapered portion 8 occupies substantially 15 inches or one third of the 75 length, and the rear cylindrical portion occupies substantially 30 inches or two thirds of the length.

The cylindrical portion is of substantially 80 3 inch diameter, and the front tapered portion 8 terminates at a blunt point substantially 2 inches in diameter. This tapered portion on each roll is provided with a shallow spiral rib 10 extending throughout of the tapered portion, and such rib is of a depth of 85 approximately $\frac{1}{8}$ to $\frac{1}{4}$ of an inch. The ribs of the two rolls spiral in opposite directions so that when the two rolls are rotated in opposite directions as shown by the arrows in Fig.

1 the corn stalks will be drawn down between 90 the two rolls. Furthermore, the spirals of the ribs 10 are such that with this rotation the corn stalks will be advanced along the tapered portions of the rolls and towards the rear cylindrical portions thereof. The rolls are preferably provided with approximately 95 $3\frac{1}{2}$ turns of spiral as shown in Fig. 1.

The rear cylindrical portion of each roll is provided with two diametrically opposite 100 relatively broad ribs 11 and 12 and with two

intermediate diametrically opposite relatively broad fluted ribs 13 and 14. Each roll is also provided intermediate between the positions of these ribs with companion low portions or valleys as best shown in Figs. 2 and 3; and the rolls are so timed in their rotations as to bring the rib of one roll into mesh or timing with the companion valley of the other roll. Furthermore the rolls are preferably so set with respect to each other that the ribs will enter slightly into the valleys; but the degree of such entry, if any, will depend upon the temporary setting of the rolls.

The ribs 13 and 14 are preferably fluted throughout their entire lengths with a number of relatively shallow flutes. This will materially improve the grip of the rolls on the stalks and insure proper feed of the stalks downwards through the rolls.

The body portion of each roll is preferably hollowed out as shown at 15, leaving only a relatively short hub section 16 at the front end and a relatively short hub section 17 at the rear end. The shaft is extended throughout the length of each roll being provided with shoulder 19 in its front portion, which shoulder sets against the front end of the hollowed out portion 15 of such roll. The relatively small front end 20 of the shaft projects beyond the roll and is received in an appropriate bearing.

A rivet 21 may be used for connecting each roll to its shaft as shown in Fig. 1.

The rear portions of the shafts also project beyond the respective rolls and are recessed in appropriate bearings.

While I have herein shown and described only a single embodiment of my present invention and have also made general references to size and proportions of a particular construction, it will be understood that I do not intend to limit myself thereto except as I may do so in the claims.

I claim:

1. Means for snapping ears of corn and the like from their stalks comprising in combination a pair of rolls which are relatively long as compared to their diameters, and means for journaling said rolls in relatively close proximity to each other, each roll comprising a major snapping portion of a substantially uniform size together with a minor feeding portion of size tapering from its beginning end towards its position of juncture with the major portion aforesaid, the rolls being adapted for rotation in opposite directions and in timed relationship, an even series of longitudinally extending ribs throughout each major portion aforesaid together with intermediate valleys between said ribs, alternate ribs being longitudinally fluted with relatively small flutes throughout their length, and a spiral rib on the tapered portion of each roll extending from its small front end to its larger point of junction with

the ribbed major portion aforesaid, said spiral ribs spiraling in companion directions to feed the stalks towards the major portions of the rolls, substantially as described.

2. Means for snapping ears of corn and the like from their stalks comprising in combination a pair of rolls, means for journaling the same in close proximity to each other, substantially the rear two thirds of each roll being of uniform size and provided with longitudinally extending ribs of even number together with intermediate longitudinally extending valleys, alternate ribs being longitudinally fluted with relatively small flutes, the ribs of one roll working into the valleys of the other roll as the rolls are rotated, means for driving the rolls in opposite directions and in proper timing to cause the ribs of each roll to work into the valleys of the other roll, and substantially the front one third of each roll being of tapered size and provided with a spiral rib, the spiral ribs of the two rolls being twisted in such directions as to feed the corn stalks towards the rear portions of the rolls as the rolls are rotated, substantially as described.
